United States Patent Office.

L. W. BEECHER, OF WESTVILLE, CONNECTICUT.

Letters Patent No. 95,185, dated September 28, 1869.

IMPROVED BASKET.

The Schedule referred to in these Letters Patent and making part of the same.

To all whom it may concern:

Be it known that I, L. W. BEECHER, of Westville, in the county of New Haven, and State of Connecticut, have invented a new Improvement in Baskets; and I do hereby declare the following, when taken in connection with the accompanying drawings, and the letters of reference marked thereon, to be a full, clear, and exact description of the same, and which said drawings constitute part of this specification, and present in—

Figure 1, a side view, and in

Figures 2 and 3, enlarged views of the splints, to illustrate the improvement.

This invention relates to an improvement in that class of baskets used for the transportation of fruit and vegetables, and with special reference to the basket patented to me, May 31, 1864.

Heretofore these baskets have been formed by nailing one end of a number of splints to the edge of the bottom of the basket, and uniting the splints at the top by a band or otherwise. The nailing is necessarily done very near the end of the splint, at the bottom, and in many cases splits the splints, so that after a little use the splints become detached, and the basket is rendered useless.

To overcome these difficulties is the object of my invention, and to enable others skilled in the art to understand and make the same, I will proceed to a full

description thereof, as illustrated in the accompanying drawings.

The bottom of the basket is formed in the usual manner. The splints are cut sufficiently long to make two or more lengths, then scored diagonally, as at *a*, fig. 2, which allows their being folded as seen in fig. 3, leaving a double edge at the bottom, and a double surface, *B*, (see fig. 3,) through which the splints are nailed to the edge of the bottom. The grain of the wood being crossed by the doubling, and the end thereby protected, a single nail holds the two splints, and without any liability of their splitting or becoming detached by use.

Several splints thus folded are placed around and secured to the bottom of the basket, as seen in fig. 1, and, extending up, are gathered into and secured by the band *C*, and the basket is complete.

Having thus fully described my invention,

What I claim as new and useful, and desire to secure by Letters Patent, is—

In the construction of baskets, the splints diagonally scored and folded at the lower ends, so as to be secured to the bottom, substantially as and for the purpose specified.

L. W. BEECHER.
